(57) **CLAIM**

The ornamental design for an ashless tray, as shown and described.

DESCRIPTION

FIG. 1 is an isometric view of the ashless tray showing our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top view thereof; and,

FIG. 7 is a bottom view thereof.

The broken lines in the drawings depict parts of the ashless tray that form no part of the claimed design.
